CLAIM

The ornamental design for a fishing lure, as shown and described.

DESCRIPTION

FIG. 1 is a front perspective view of a fishing lure.

FIG. 2 is a rear perspective view thereof.

FIG. 3 is a front elevation view thereof.

FIG. 4 is a rear elevation view thereof.

FIG. 5 is a right-side elevation view thereof.

FIG. 6 is a left-side elevation view thereof.

FIG. 7 is a bottom plan view thereof.

FIG. 8 is a top plan view thereof; and,

FIG. 9 is a top plan view thereof with a rear portion rotated into an alternate position.

Broken lines in the drawings illustrate portions of the fishing lure that form no part of the claimed design.
